UNITED STATES PATENT OFFICE.

JACK KLEINMAN, OF BRONX, NEW YORK, ASSIGNOR TO HENRY HYMAN & CO., INC., OF NEW YORK, N. Y., A CORPORATION OF NEW YORK.

TELEPHONE RECEIVER.

Application filed March 24, 1923. Serial No. 627,519.

My invention relates to telephone receiving instruments and more particularly for instruments adapted for use in the reception of radio signals or sounds.

One object of my invention is to provide a simple means of adjustment for increasing and decreasing the distance between the diaphragm and core piece or pieces of the electro magnet or magnets. Another object is to provide a simple means of connecting the ends of a telephone receiver cord in a receiver. Other objects will appear in the description of the invention which follows:

Referring to the drawings which form a part of this specification.

Fig. 1 is a plan view of my diaphragm and armature.

Fig. 2 is a plan view of my telephone cord connecting piece, as used in a receiver case.

Fig. 3 is a vertical sectional view of the receiver embodying my inventions.

Fig. 4 is a fragmental sectional view of another means of adjustment.

In the drawings A indicates my armature with an extending arm A' to the center. A² indicates a diaphragm of non-magnetic material riveted or welded or otherwise attached as at B at the center to armature A.

C indicates a threaded stud riveted or spot welded or otherwise attached to armature at A³. A spring D is provided to press the diaphragm away from the magnet core G while a nut F on stud C may be provided to draw the diaphragm toward the core. Thus the proper adjustment of distance between the diaphragm and magnet may be effected. As shown, the diaphragm is pressed tightly between the casing E and cap L, so that the action of spring D and stud C causes the diaphragm to bulge one way or another from the middle.

H indicates my receiver cord connecting piece with a hole in the center and with two extended arms H' curled at the end as at H² to securely grip the ends of the receiver cord J. The ends G² of the winding of the magnet coil G' may be soldered to the ends of the cord J as indicated.

L indicates the cap preferably of hard rubber or vulcanite threaded in the usual manner to fit casing E and clamps armature A and diaphragm A² at point L' as set forth.

M indicates permanent magnets surrounding coil winding G' and core G and in juxtaposition to core G at its base. 55

N indicates a screw which enters through the hole in the center of casing E through the hole in cord connecting piece H and into the threaded portion of core piece G. In this manner, core piece G with its winding 60 G', permanent magnets M, and cord connecting piece H are clamped firmly to case E.

As shown in Figure 4, the adjustment of the diaphragm may be effected by a stud C' having a head O fixed thereto and threaded 65 in the back of the casing or in a boss K integral with the casing. Turning of stud C' one way will thus force the diaphragm away from the magnets, while turning in the other direction will permit it to spring back to 70 toward the magnets.

I claim:

1. In a telephone receiver, a casing, an electro-magnet therein, a non-magnetic diaphragm in the casing and centrally disposed 75 over the magnet, a magnetic ring concentric with the diaphragm and having its periphery held in the casing, said ring having a tongue extending to the center of the diaphragm with its inner end attached to the 80 diaphragm and an adjusting member attached to the tongue and extending through the casing at one side of the magnet and arranged to adjust the tongue and the diaphragm toward and away from the magnet. 85

2. In a telephone receiver, a casing, an electro-magnet secured within said casing, and a wire-securing member clamped between the magnet and casing and having arms arranged to hold wires connected to 90 the magnet.

3. In a telephone receiver, a casing, an electro-magnet therein, securing means extending through the casing and arranged to draw the magnet toward the wall of the 95 casing, and a sheet metal wire securing member having a body portion between the magnet and the wall of the casing and having outwardly extending arms arranged to hold wires connected to the magnet. 100

Signed at New York, in the county of New York and State of New York, this 23rd day of March A. D., 1923.

JACK KLEINMAN.
